UNITED STATES PATENT OFFICE.

PAUL MOOSMANN, OF BROOKLYN, NEW YORK.

DUST-CAP FOR BALANCE-ESCAPEMENTS.

SPECIFICATION forming part of Letters Patent No. 718,369, dated January 13, 1903.

Application filed May 22, 1901. Renewed May 16, 1902. Serial No. 107,566. (No model.)

To all whom it may concern:

Be it known that I, PAUL MOOSMANN, a citizen of the United States, residing in New York, borough of Brooklyn, in the State of New York, have invented certain new and useful Improvements in Dust-Caps for Balance-Escapements, of which the following is a specification.

This invention relates to improvements in dust-caps for balance-escapements; and the object of the invention is to provide means for protecting the escapement against dust and for regulating the escapement without impairing the complete protection against dust during the regulating operation; and the invention consists in the combination, with a balance-escapement, of a dust-cap for the same, consisting of a cap having an opening, means closing said opening, and means connected with said closing means and engaging the regulator-arm of the escapement; and the invention consists, further, in certain other combinations of parts, which will be fully described hereinafter and finally pointed out in the claim.

In the accompanying drawings, Figure 1 is a front view of a clock provided with my improved dust-cap. Fig. 2 is a plan view of the clock, drawn on a larger scale. Fig. 3 is a plan view of the escapement shown in Fig. 2 with the dust-cap removed; and Fig. 4 is a vertical transverse section on line 44, Fig. 2.

Similar letters of reference indicate corresponding parts.

Referring to the drawings, A represents the movement of a clock, the balance-escapement of which is made of any approved construction and protected by my improved dust-cap. D represents the dial, which is supported by posts of the frame of the clock-movement in the usual manner. The upper part of the dial is provided above the numeral "XII" with a graduated scale d, located below a recess of the dial. In the recess the uppermost end of an adjusting-lever L is visible and located so as to be readily adjusted according to the graduations. The upwardly-extending lever L is bent at a right angle to the lower part, and said lower part is shown integral with a plate l, which serves as means for closing the arc-shaped slot e' in the top of the dust-cap C. Said plate l is pivoted to the dust-

cap, the pivot being preferably in line with the pivot of the regulator-arm e², as shown, and said dust-cap is provided with a circumferential flange, by which it is attached to the bridge B. The escapement is supported on the bridge B and the latter by the plates A' A² of the clock-frame. The balance-wheel b of the escapement is made of any suitable construction and turns by its arbor in the balance-bridge b' and the escapement-bridge B. The cap C is recessed at that portion where it extends over the base of the balance-bridge and is fitted tightly to the same and to the bridge B, so as to prevent ingress of dust. To the plate l are applied at the under side two pins e, which pass through the opening e' to the inside of the cap and serve as means for engaging the regulator-arm e², whereby by moving the plate l by means of its operating-lever L the regulator-arm is shifted and the speed of the clock regulated, without, however, permitting any ingress of dust within the cap at any time, said plate l being of such shape and size as to always close said opening e' in whatever position the pins may be in said opening. The plate l fits tightly down upon the top of the cap and by its large contact-surface with the same effectually prevents ingress of dust through the opening e'.

The dust-cap and the means described for closing the same and operating the regulator-arm of the escapement without permitting ingress of dust form a valuable protection to the escapement and render the same capable of being used for years without cleaning or repairing. The dust-cap is especially useful when applied over the escapements of chronometers, locomotive-clocks, and timepieces for sailing and steam vessels, as it protects the escapement from dust and retards evaporation of the oil, so that the timepiece is kept in running order for a much longer time than were the escapement exposed.

Having thus described my invention, I claim as new and desire to secure by Letters Patent—

The combination, with a balance-escapement, of a dust-cap for the same, consisting of a cap having an arc-shaped slot, a plate pivoted to said cap and closing said slot, pins projecting from said plate and extending through said slot into engagement with the

regulator-arm of the escapement, said plate extending at each side of said pins for a distance equal to the full length of said slot, a balance-wheel and regulator-arm pivoted in the same central line with said plate, a graduated scale, and an operating-lever connected with said plate and movable over said scale, substantially as set forth.

In testimony that I claim the foregoing as my invention I have signed my name in presence of two subscribing witnesses.

PAUL MOOSMANN.
